ATTORNEY.

UNITED STATES PATENT OFFICE.

HENRY M. GLEASON, OF PHILADELPHIA, PENNSYLVANIA.

PROJECTILE.

939,682.

Specification of Letters Patent.

Patented Nov. 9, 1909.

Application filed October 20, 1906. Serial No. 339,756.

To all whom it may concern:

Be it known that I, HENRY M. GLEASON, a citizen of the United States, residing at Philadelphia, in the county of Philadelphia and State of Pennsylvania, have invented a new and useful Projectile, of which the following is a specification.

My invention relates to improvements in projectiles.

10 The object of my invention is to provide means for causing the rotation of the projectile around its longitudinal axis or at right angles to the line of its travel by the passage of gas through said projectile from the rear thereof in one or more longitudinally extending spiral paths, said projectile being especially adapted for use in smooth bore guns.

Referring to the drawings:—Figure 1 is 20 a side elevation of my device in part section. Fig. 2 is a rear elevation.

Similar numerals refer to similar parts throughout the several views.

My invention comprises an improvement 25 in the production of projectiles which may be fired from a smooth bore gun and still acquire the rotary motion which is ordinarily given to a projectile by the rifling of the gun.

My invention comprises a method for giving 30 the rotary motion to the projectile in a smooth bore gun by causing the passage of gas through the projectile from the rear thereof in one or more longitudinally extending spirally directed paths.

35 A convenient way of forming such a projectile is clearly illustrated in Fig. 1, in which 3 represents a cylindrical body pointed at one end in the usual form of such projectiles. The base 8 is threaded into the shell for 40 closing the charged chamber 10 which is in the usual form and needs no further mention in this connection. In this body 3 are formed a series of longitudinally extending channels or grooves 7 spirally directed from the rear of the body to near its front end. Over this body 3 is shrunk the metallic jacket 4, forming said channels into a plurality of 45 passages opening at the rear of the body and also near the front, or conical shaped end, as indicated at 9. Near the rear of the body now formed by members 3 and 4, that is, in the surface of the jacket 4 is provided the soft metal or copper band 5, which serves as a gas check for preventing the escape of 50 gas around the projectile when the charge is fired in the gun. Near the forward part of

the body, that is, around the forward part of jacket 4 is provided another soft metal or copper band 6 for the purpose of centering the projectile, that is, keeping the axis of the projectile coincident with that of the bore of the gun. These soft metal rings also serve to prevent the harder metal of the projectile from coming in contact with the surface of the bore of the gun.

On account of the high powder pressure and resultant high temperature employed in rifled guns of large caliber the life of the rifling of the gun is very limited. The limit of its life may be said to depend mainly 65 upon the capacity of the rifling to withstand the wearing effect of the projectile, and the erosive effect of the gas produced by the combustion of the powder.

The erosion in modern large caliber guns 70 is so pronounced that these guns must be re-lined and re-rifled after a comparatively few number of rounds have been fired. The cost of re-rifling a large caliber gun is considerable, and there is, besides, a resultant 75 loss of military efficiency in that the gun is out of service during the process.

It is very probable that a great portion of the trouble experienced with erosion, is due to the rifling in the bore; and by the elimination of rifling from the bore, erosion will 80 be obviated to a great extent. With this in view, I have provided my improved projectile, so constructed that it will acquire a rotary motion within itself, when fired from 85 the gun, and thus do away with the necessity of rifling.

In a rifled gun about fifteen per cent. of the energy of the powder charge is consumed in forcing the projectile through the 90 bore and the rifling. In the smooth bore gun with the projectile herein described it is proposed to use a portion of this lost energy to produce the desired rotation of the projectile, and to overcome the friction of rotation due to "forcing" which need be only sufficient to prevent the escape of gas between the rear band on the projectile and the bore of the gun.

The rear band 5 of the projectile which 105 acts as a gas-check is slightly greater in diameter than the bore of the gun. This is to allow for the expansion of the bore under pressure. The forward band 6 is slightly less in diameter and, as above stated, is 110 adapted to maintain the projectile with its axis coincident with the axis of the bore of

the gun and also to prevent the hard metal jacket of the shell from wearing the surface of the bore.

The energy of rotation is obtained by the 5 action of the escaping gas from the explosion of the charge by allowing a portion of this gas to pass through the spiral channels or passages 7, which serves to give a twist to the projectile as the same is passing

10 through the gun.

The sleeve or jacket 3, around the body of the projectile, prevents the high pressure gas, while escaping, from coming in direct contact with the surface of the bore. This 15 feature will prevent the erosion of the bore, which would be excessive if the gas was allowed to escape through the grooves on the surface of the projectile in direct contact with the bore of the gun. It is obvious 20 that there may be one or more of such spiral paths, and that the number, size and contour of the grooves 7, may be varied to suit required conditions.

What I claim is:—

- 25 1. A projectile, comprising a cylindrical body provided with spiral grooves on its surface, and a metal jacket shrunk over said body and covering said grooves throughout the entire cylindrical portion of said body 30 so as to form passages opening at the rear of the body and also near the front end thereof, said passages adapted to permit the escape of gas through the projectile from the rear thereof.
- 35 2. A projectile, comprising a body having grooves on its periphery extending from the rear to near the front thereof, said grooves being straight near the rear of the projectile and spiral near the front thereof, and a 40 metal jacket covering said grooves.
3. A projectile for use with smooth bore

guns, comprising a cylindrical body provided with spiral grooves on its surface, a metal jacket covering said grooves so as to form passages opening at the rear of the body and also near the front end thereof, and a solid band of soft metal around the periphery of said jacket to form a gas check.

4. A projectile for use with smooth bore guns, comprising a cylindrical body provided with spiral grooves on its surface, a metal jacket covering said grooves so as to form passages opening at the rear of the body and also near the front end thereof, and a solid band of soft metal around the periphery of said jacket near its forward end to form a centering band.

5. A projectile for use with smooth bore guns, comprising a cylindrical body provided with spirally arranged passages extending from the rear to near the front of said body and a solid band of soft metal around the periphery of its body near its rear end to form a gas check and a similar soft metal band around the periphery of its 65 forward end to form a centering band.

6. A projectile for use with smooth bore guns, comprising a cylindrical body provided with spiral grooves on its surface, a metal jacket covering said grooves so as to 70 form passages opening at the rear of the body and also near the front end thereof, a solid band of soft metal around the periphery of said jacket to form a gas check, and a similar soft metal band around the periphery of said jacket near its forward end to form a centering band.

HENRY M. GLEASON.
